SELECTOR FOR SORTING MACHINES

William C. Silver, Kansas City, Mo.

Application June 20, 1936, Serial No. 36,393

8 Claims. (Cl. 209—110)

This invention relates to sorting machines for record cards, and the primary object is to provide in such a machine, a plurality of analyzing elements, each of which is controlled by one of the record cards as a large number of said cards pass into the machine, to the end that disposition of one of the cards being analyzed is determined by the relative natures of the cards which are simultaneously in engagement with the analyzing elements.

Another important aim of this invention is to provide, in a sorting machine of the conventional type, a plurality of analyzing elements, electrically interconnected in such manner as to cause disposition of one of the record cards according to the structural relationship thereof with respect to cards which have preceded it into the machine, one of which co-operates with the said card being acted upon in making or breaking the electrical circuit having the said analyzing elements therein.

A yet further object of this invention is the provision, in a sorting machine of the conventional type, having a single analyzing element of a co-operating analyzing element, the action of which is controlled by a record card passing into the machine ahead of the record card that is being engaged by the customary analyzing element so that no duplicate cards will remain in a stack of record cards after the same have passed into the machine.

Minor objects of the invention and the manner of attaching the supplementary analyzing means will appear during the course of the following specification, referring to the accompanying drawing, wherein:

Figure 1 is a schematic view, illustrating a part of a sorting machine having analyzing elements disposed as contemplated by this invention, and,

Fig. 2 is a diagrammatical view illustrating the electrical circuits and a group of adjacent cards, all of which co-operate with the two analyzing elements that are interposed in the circuit.

Sorting machines of the character upon which parts embodying this invention might be mounted are known in the art, and so far as I am aware, there has never been means in such sorting machines for removing duplicate cards from a stack of record cards, so that when the cards of the stack had been run into the machine, one of the pockets thereof will contain cards of different natures. In practice, duplicate record cards not desired have had to be removed from the stack by hand, and as a result of this short-

coming in the sorting machine, a vast amount of time is consumed when it becomes necessary to remove from the record cards, the duplicates which have been placed therein as a result of fulfilling some bookkeeping requirement which necessitates making up a record card which is a duplicate of one already in the stack.

Record cards 4 are each provided with a series of figure columns, such as shown in Fig. 2, and which are of well known type. Perforations 6 are provided in the record cards at different locations thereon so that the operator, by glancing at the record card, can at once conclude what number is designated by the punchings or perforations therein. Throughout this specification and the claims, reference to relative natures of cards 4 must be construed to be the relative positions of perforations 6, which combine to designate a particular number.

There is but one complete number designated by each card 4, and the cards to be sorted are placed in a magazine 8 and fed from the bottom thereof by a feeding device 18, which projects the lowermost card 4 into the machine between upper rollers 12 and lower rollers 14. These rollers are driven in the direction indicated by the arrows in Fig. 1 at a very rapid rate of speed, and the cards are successively fed into the machine, and in the final analysis dropped into the plurality of card-receiving pockets 16, each of which is associated with one of the distributing passages 18, the receiving ends of which are opened or otherwise made ready to receive one card 4 after it passes through the main analyzing element 20.

This analyzing element essentially comprises means for making and breaking an electric circuit, and arm 22 carries brush 24 so that it rides over the periphery of roller 26. A brush 28 is in frictional engagement with roller 26 and as one of record cards 4 passes between brush 24 and roller 26, the presence or absence of a perforation 6 will determine whether or not the circuit is opened or closed and the exact location of perforations 6 will govern the opening of the receiving end of one of the distributing passages 18.

When attaching structure embodying this invention to the regular sorting machine now in common use, the receiving pocket 16 closest to analyzer 20 is not used and pocket normally numbered 12 will be used as a "reject" pocket.

To fulfill the principal object of the invention, a second analyzing element 30 is placed so that its brush 32 will ride over one of the record cards 4 the same time that the following record card 55

is being engaged by brush 24. Brush 32 is mounted for lateral adjustment in precisely the same way as brush 24 and the bracket 34 may be carried on a transverse shaft 36 that is attached to the sides 38 of the machine.

5 A table 40 is also attached to sides 38 and insulated therefrom so that brush and table 32 and 40 respectively might be interposed in the circuit with brush and roller 24 and 26 respectively. Thus when a series of cards is passing into the machine, two adjoining cards will be simultaneously analyzed and the relative natures of the two cards will determine the pocket receiving one of said cards. It will be made clear 10 at a later point, the manner in which a third card preceding the two cards being simultaneously analyzed will enter into the combination of rejecting duplicates and maintaining only cards of unlike natures in one of the card receiving 15 pockets.

20 Means for opening or conditioning the receiving ends of distributing passages 18 is electrical- 25 ly operated, and for purpose of exemplification, the electro-magnet 42 is shown as a part of the complete circuit. The force exerted when this 30 electro-magnet 42 is energized may be transmitted to the mechanical elements 44 of the machine, which open the receiving ends of passages 18. The electrical connections involved when 35 making a sorting machine embodying the improvements will consist of a wire 46 connecting brush 28 and brush 32, a wire 48 joining table 40 and electro-magnet 42, a wire 50 extending from electro-magnet 42 to one side of a source 40 of electrical supply 52, and a wire 54 joining the other side or line 56 with brush 24.

45 In the instance exemplified in Fig. 2, the circuit is completed and closed because perforations 6 of successive adjoining cards are in the same 50 relative location on the cards and, therefore, brushes 24 and 32 are allowed to contact roller 26 and table 40 respectively. Obviously, electro- 55 magnet 42 will be energized by the closing of the circuit through wire 54, brush 24, roller 26, brush 28, wire 46, brush 32, wire 48, electro-magnet 42, and wire 50.

50 One of the distributing passages 18 leading to a card-receiving pocket which corresponds to the number 6 which has been punched will, therefore, receive the last card or the one being analyzed by analyzing element 28. Because of the 55 nature of the third or "lead" card, the card being analyzed by element 30 will be in the passage 18 leading to pocket 16, which is the "reject" 60 pocket and the one that is used to receive all of cards 4 from the magazine which are not duplicates of other cards. The card to the right in Fig. 2 will obviously pass to pocket 16 for number 6 cards and, after the pack of cards has been 65 run through the machine, it will be known that this card is a duplicate of one that forms a part of the group of cards in the reject pocket from which all duplicates have been removed.

65 As an explanation of the immediate foregoing statement with respect to the middle card (Fig. 2) being within a distributing passage 18 which is directing the card to the reject pocket, a transposition of the three cards one step to the right must be pictured in order to make it apparent that the circuit cannot be closed when the cards are so transposed or moved back one step and, therefore, the central card of the group of three illustrated, will pass into distributing passage 18 leading to the reject pocket.

70 In short, whenever a card passes beyond main

75 analyzing element 20 with the circuit open, it is destined for the reject pocket and, in gaining the advantage of this invention, that is the pocket where all cards not being duplicates are deposited. Obviously, since the two cards to the left of the three illustrated are being simultaneously analyzed, and since perforations 6 of the two cards are not in like positions thereon, it will be impossible for the two brushes 24 and 32 to close the circuit and, therefore, the central 10 card, being this time the lead card ahead, will follow said lead card to the pocket-receiving cards of different natures, but as soon as cards of duplicate natures, such as in the case illustrated, are presented for simultaneous analysis, 15 a duplicate card will at once be detected and it (being the right hand card in Fig. 2) will be rejected or removed from the stack as a duplicate and sent to one of the other card-receiving pockets for disposition as the operator desires. 20

It is conceivable that if a number of cards, 25 duplicate in nature to those two being analyzed, should follow the last card entering the machine, that they too would be passed to a card-receiving pocket other than the "reject" pocket, and there 30 would be left in the reject pocket, only one of that nature of card.

35 The first card sent into the machine is always a blank card without punching in the column being analyzed so that brush 32 is insulated from 40 plate 40 until the second card or first punched card is under brush 32 for analysis. Such positioning of a blank card as a first one will obviously permit the next two punched cards to locate beneath brushes 24 and 32 respectively to 45 co-operate in controlling the circuit in the manner herein set down.

50 The two analyzing elements are in tandem, or one in alignment with the other, so that the same column of figures on the two cards being analyzed are traversed by the brushes.

55 A large number of advantages arise from the employment of such equipment in sorting machines, and while one embodiment of the invention has been exemplified, it is understood that 45 changes and modifications might be made without departing from the spirit of the invention or scope of the appended claims.

60 Having thus described the invention, what is claimed as new and desired to be secured by 50 Letters Patent is:

65 1. In a sorting machine having card feeding devices for successively carrying cards into the machine, a plurality of card-receiving pockets, and distributing passages leading to the pockets, 55 the combination of electrical means having spaced-apart brushes for simultaneously, individually analyzing a plurality of the cards, and means operated by said analyzing means to open the receiving end of one of the distributing passages for one of the cards being analyzed, the relative natures of the plurality of cards being analyzed determining the pocket receiving one of said cards, said distributing passages having their receiving ends between said spaced-apart 60 brushes.

70 2. In a sorting machine having card feeding devices for successively carrying cards into the machine, a plurality of card-receiving pockets, and distributing passages leading to the pockets, 70 the combination of electrical analyzing means having brushes for simultaneously, individually sweeping corresponding parts of a pair of cards, and means operated by said analyzing means to open the receiving end of one of the distributing 75

- passages for one of the cards being analyzed when the cards of the pair are of a like nature, at least one of the cards being analyzed being within one of the distributing passages.
5. 3. In a sorting machine having card feeding devices for successively carrying cards into the machine, a plurality of card-receiving pockets, and distributing passages leading to the pockets, the combination of electrical analyzing means 10 having brushes for simultaneously, individually sweeping corresponding parts of each of a plurality of cards, and means operated by said analyzing means to open the receiving end of one of the distributing passages for one of the cards being analyzed when the cards are of a like nature, at least one of the plurality of cards being analyzed being within one of the distributing passages, another of said cards being analyzed being outside of the plurality of distributing passages, the relative natures of the plurality of cards being analyzed serving to effect the analyzing means to determine the passage and pocket receiving the outside card.
4. In a sorting machine having card feeding devices for successively carrying cards into the machine, a plurality of card-receiving pockets, distributing passages leading to the pockets, means for analyzing each card prior to its entry into a passage, electrical means, including a circuit opened and closed by the analyzing means, to cause the card to enter one of the distributing passages, the combination of a second analyzing element interposed in the said circuit to analyze the same part of the said card after the same has been analyzed by the first mentioned analyzing means and has passed into one of the passages, said second analyzing element being positioned to act upon parts of the card while corresponding parts of the next succeeding card are being analyzed by the first mentioned analyzing means.
5. In a sorting machine having card feeding devices for successively carrying cards into the machine, a plurality of card-receiving pockets, distributing passages leading to the pockets, means for analyzing each card prior to its entry into a passage, electrical means, including a circuit opened and closed by the analyzing means, to cause the card to enter one of the distributing passages, the combination of a second analyzing element interposed in the said circuit to analyze the said card after the same has been analyzed by the first mentioned analyzing means and has passed into one of the passages, the first mentioned analyzing means acting upon the next succeeding card being fed into the machine as the said first card is being analyzed by the second analyzing means.
6. In a sorting machine having card feeding devices for successively carrying cards into the machine, a plurality of card-receiving pockets, distributing passages leading to the pockets, means for analyzing each card prior to its entry into a passage, electrical means, including a circuit opened and closed by the analyzing means, to cause the card to enter one of the distributing

passages, the combination of a second analyzing element interposed in the said circuit to analyze the said card after the same has been analyzed by the first mentioned analyzing means and has passed into one of the passages, the first mentioned analyzing means acting upon the next succeeding card being fed into the machine as the said first card is being analyzed by the second analyzing means, said circuit being closed by both analyzing means, to render effective the electrical means for causing one of the cards to enter one of the distributing passages, when the two cards being analyzed are of a like nature.

7. In a sorting machine having card feeding devices for successively carrying cards into the machine, a plurality of card-receiving pockets, distributing passages leading to the pockets, means for analyzing each card prior to its entry into a passage, electrical means, including a circuit opened and closed by the analyzing means, to cause the card to enter one of the distributing passages, the combination of a second analyzing element interposed in the said circuit to analyze the said card after the same has been analyzed by the first mentioned analyzing means and has passed into one of the passages, the first mentioned analyzing means acting upon the next succeeding card being fed into the machine as the said first card is being analyzed by the second analyzing means, said circuit being maintained open by at least one of the analyzing means, to render ineffective the electrical means for causing the cards to enter one of the distributing passages, when the two cards being analyzed are of an unlike nature but each individually capable of causing one of the said means to close the circuit thereof.

8. In a sorting machine having card feeding devices for successively carrying cards into the machine, a plurality of card-receiving pockets, distributing passages leading to the pockets one of which is always open to receive the cards, means for analyzing each card prior to its entry into any passage, electrical means, including a circuit opened and closed by the analyzing means, to cause the card to enter one of the distributing passages other than the said one passage, the combination of a second analyzing element interposed in the said circuit to analyze the said card after the same has been analyzed by the first mentioned analyzing means and while the first mentioned analyzing means is acting upon the next succeeding card, said second analyzing element being positioned to act upon parts of a card while corresponding parts of the next succeeding card are being analyzed by the first mentioned analyzing means, either of said analyzing means being capable of opening and closing said circuit when the other analyzing means is in the circuit closing position whereby the first card of a group of cards, similar in operating effect upon the two analyzing means, will enter the said one open passage and the next succeeding cards of the group will be directed into one of the other distributing passages.
